J. G. Smith

UNITED STATES PATENT OFFICE

MELVIN DILL, OF LYNN, MASSACHUSETTS, ASSIGNOR TO HARRY A. HALEY, OF PLYMOUTH, MASSACHUSETTS

LEVEL

Application filed February 1, 1930. Serial No. 425,279.

This invention relates to an improvement in levels and has as its primary object to provide a novel construction of level in which the bubble tubes may be illuminated so that the level may be more conveniently employed in cellars and other places where it might be impracticable to observe with any degree of accuracy the position of the air bubble in the tube or tubes.

10 Another object of the invention is to provide a level embodying an arrangement of tubes, one set being adapted to be employed when the level is disposed against a horizontal surface and other sets of tubes being employed when the level is disposed against a vertical surface, and means being provided for illuminating the first mentioned set of tubes and one of the two other sets of tubes.

Another object of the invention is to provide in a level of the class above referred to, such an arrangement of parts that all of the component parts of the level and the illuminating means for the tubes will be located within the bounds of the stock of the level 25 so that none of the parts or elements will interfere with the proper use of the level.

This invention also consists in certain other features of construction and in the combination and arrangement of the several parts, to be hereinafter fully described, illustrated in the accompanying drawings, and specifically pointed out in the appended claim.

In describing my invention in detail, reference will be had to the accompanying drawings wherein like characters denote like or corresponding parts throughout the several views, and in which:—

Figure 1 is a view in side elevation of the level embodying the invention, the same being vertically disposed.

Figure 2 is a vertical transverse sectional view through the level.

Figure 3 is an end view of the level.

Figure 4 is a horizontal sectional view, in detail, on the line 4—4 of Figure 2, looking in the direction indicated by the arrows.

The stock of the level is indicated by the numeral 1 and it may, if desired, be formed of counterpart longitudinal pieces 2 recessed

to accommodate a filler 3, and these parts may all be removable at the time of manufacture of the level and united to one another by any suitable means and certain of the contacts, the conductor wires, and their parts 55 may be arranged within or upon or between the parts of the stock thus obviating the formation of grooves in the outer surface of the stock to accommodate conductor wires or other parts, and it will be evident that instead of wood, the stock may be in the nature of a one piece structure and may be made of metal, a composition, or any other moldable material found suitable for the purpose.

The stock 1 is formed at points at opposite sides of a point midway between its end, with recesses 4 which extend longitudinally thereof and which open through the two side faces of the stock, and a circular opening 5 is formed transversely in the stock midway 60 between the relatively adjacent ends of the slots 4, and a similar opening 6 is formed in the stock near the outer end of each slot 4. Arranged concentrically within the opening 5 and each of the openings 6 at the opposite 65 sides of each opening are transparent glass panes 7 which are circular in form and these panes are embedded at their margins in a filling 8 of putty, as also are the ends of the bubble tubes 9 of the level, and the surface of the putty filler 8 which is presented about the wall of each opening, is pure white in color so as to be capable of reflecting light rays.

At one side of the opening 5 and the corresponding side of one of the openings 6, means is provided for illuminating the bubble tubes in said openings, these tubes being arranged in parallelism in each opening, and this means comprises a substantially conical bushing 10 which is seated in the respective opening 11 formed at the said sides of the opening 5, a small circular pane 12 of clear glass being arranged at the outer end of each bushing 10 so as to transmit light rays 80 issuing from a light bulb 13, the socket for which is preferably embedded in a putty filling 14 in the inner end of the opening. A plate 15 is arranged within that end of each of the slots 4 at which the inner ends 90

- of the openings 11 are located, and conductor wires 16 are led between two of the layers 2 and 3 or in a channel 17 which may be provided in the opposing faces of the 5 pieces or layers 2 of the stock and closed by the ply 3, these conductor wires, at one side, being connected to contacts 18 which are arranged within the stock at one side of each of the slots 4. The numeral 19 indicates a contact member in the form of a 10 resilient strip of sheet metal which has a substantially semicircular portion 20 secured at one end by a screw 21 within each of the slots 4 at the side wall thereof, and 15 screws 22 at the other side of said slot, the intermediate portion of the bend engages one of the contacts of the respective bulb socket through the medium of a small contact point 23 provided upon said bend.
- 20 The other end of the strip 19 is sprung inwardly from the wall of the slot to which it is secured and normally spaced from the contact 18, this end being indicated by the numeral 24 and constituting a finger piece 25 which may be pressed inwardly so as to engage the contact 18 and close the circuit through the bulb socket. The conductor wires are led from the contacts and from the contact 15 to binding posts 25 upon the 20 plate 26 arranged within the inner end of a bore 27 formed in one end of the stock and a small dry cell 28 is arranged within this bore and has its terminals held in engagement with the binding posts 25 through the 25 medium of a compression spring 29 which bears at one end against one end of the cell and at its other end against a closure plate 30 which is slidably fitted at its side margins in grooves formed in a cover or cap 31, which is mounted upon the end of the stock, it being understood that this closure plate 30 may be slid to open position by engaging the tip of one's finger in the recess 32 formed in the outer side thereof 40 and sliding the same out of engagement with the cap 31.
- 45 It will now be evident that by pressing the spring contact fingers 24 the circuit may be closed through the light bulbs selectively, so as to illuminate any of the tubes.
- 50 Flanged brass strips 33 are provided along the corners of the stock so as to cover and protect the wood of the stock at these points.
- 55 What I claim is:—
- 55 A level comprising a stock including companion sections having an opening and a slot and in communication with each other by a lamp chamber, means securing the sections of the stock together, bubble tubes in 60 the opening, a lamp socket in the chamber, an electric lamp in the socket to furnish light to the tubes, a contact member having a semicircular-shaped portion secured to opposite walls of the slot adjacent one end 65 of the latter and bearing against the socket

and having the remaining portion offset to provide a movable contact member spaced from one of the side walls of the slot, an electrical source in the stock, conductors between the sections of the stock and connected to the source and one conductor secured to the socket, and a stationary contact secured to the other conductor and the stock to be engaged by the movable contact member for completing the circuit to the 70 lamp.

75 In testimony whereof I affix my signature.
MELVIN DILL.
